COMBINED STIMULATING AND CLEANING DEVICE

Medard W. Welch, 1111 Sheridan Road,
Winnetka, Ill. 60093

Filed Jan. 20, 1971, Ser. No. 108,254

Term of patent 14 years

Int. Cl. D24—05, 99

U.S. Cl. D83—1

FIG. 1.

FIG. 3.

FIG. 2.

fig.6.

FIG. 1 is a perspective view of a combined stimulating and cleaning device showing my new design;

FIG. 2 is a perspective view, like FIG. 1, with the top open;

FIG. 3 is a front elevational view thereof with the top closed;

FIG. 4 is a left side elevational view thereof with the top closed;

FIG. 5 is a top plan view thereof;

FIG. 6 is a top plan view thereof with the top open and the hand piece removed;

FIG. 7 is a left side elevational view thereof with the top open;

FIG. 8 is a front elevational view thereof with the top open; and

FIG. 9 is a rear elevational view with the top closed.

I claim:

The ornamental design for a combined stimulating and cleaning device, as shown and described.
